(57) **CLAIM**

The ornamental design for a lens bracket, substantially as shown and described.

DESCRIPTION

FIG. 1 is a front, right, and bottom perspective view of a lens bracket showing my new design;

FIG. 2 is a rear, left, and bottom perspective view thereof;

FIG. 3 is a front elevational view thereof;

FIG. 4 is a right side elevation view thereof;

FIG. 5 is a top plan view thereof;

FIG. 6 is a rear elevational view thereof;

FIG. 7 is a bottom plan view thereof; and,

FIG. 8 is a left side elevation view thereof.

The broken lines and unshaded areas in the drawings depict portions of the lens bracket that form no part of the claimed design.
